UNITED STATES PATENT OFFICE.

JOHN W. SPRINKLE, OF PHILADELPHIA, PENNSYLVANIA.

RESONATING ATTACHMENT FOR SOUNDBOARDS.

1,258,491.

Specification of Letters Patent. Patented Mar. 5, 1918.

Application filed October 12, 1916. Serial No. 125,274.

To all whom it may concern:

Be it known that I, JOHN W. SPRINKLE, a citizen of the United States, residing at Philadelphia, in the county of Philadelphia and State of Pennsylvania, have invented 5 new and useful Improvements in Resonating Attachments for Soundboards, of which the following is a specification.

This invention relates to musical instruments, and has particular reference to improvements in the soundboards of pianos.

An object is to provide a piano soundboard with an associated resonator having a stylus in physical contact with vibratory 15 portions of the soundboard, whereby the vibration of the latter will be transmitted to the resonator.

A further object resides in providing means for regulating and maintaining pressure between the bridge of said resonator 20 and the soundboard, whereby the vibrations of the latter will be transmitted to the resonator.

Other objects will be in part obvious and 25 in part pointed out hereinafter.

The invention accordingly consists in the features of construction, combination of elements and arrangement of parts which will be exemplified in the construction herein described and indicated in the following 30 claim.

In the accompanying drawings, wherein is shown one of the various possible embodiments of the invention,

Figure 1 is a rear elevation of a piano illustrating the application of the resonator, comprising the present invention, to the soundboard of a piano,

Fig. 2 is a vertical longitudinal sectional view taken along the line 2—2 of Fig. 1, and

Fig. 3 is a horizontal sectional view taken along the line 3—3 of Fig. 1.

Similar characters of reference denote corresponding parts throughout all the 45 views of the drawing.

Referring more particularly to the drawing, the numeral 1 designates a piano frame to which is suitably secured, in any convenient manner, the usual soundboard 2, the 50 latter being of any standard design and construction. The various functions of the members 1 and 2 are, of course, generally understood and therefore it will not be necessary to specifically describe their purposes.

One or more resonators 4 are arranged in

physical contact with the soundboard 2. It will be understood that a plurality of the bodies 4 may be used in connection with the soundboard but, as has been shown in the 60 drawing, when only one is used very satisfactory results have been obtained.

Preferably, the body 4 is placed contiguous to the central portion of the soundboard, as it is at this point where the greatest vibration of the soundboard occurs. As shown, 65 said body is generally positioned adjacent to the back of the soundboard and is confined between the uprights 5 of the frame. However, while this location has so far been 70 found to be the most desirable, it is, of course, within the scope of the invention to locate the body 4 within or without the piano, with the only restriction that the same be placed so as to vibrate in unison 75 with the soundboard.

The resonant body 4 is preferably made from the same material and of the same general construction and contour as the body of a violin, guitar or other similar instrument. 80 The body is provided with upper and lower cross pieces 6, which extend beyond the periphery of said body. The horizontally disposed sections 7 of the cross pieces are provided, adjacent to their outer extremities, 85 with openings 8, the latter being adapted to receive the shanks of manually operated tightening bolts 9, which are rotatably mounted in openings 10 formed in brackets 11, secured to the uprights 5 of the piano 90 frame.

Formed on or secured to the inner face 12 of the body 4 is a bridge 13 which is disposed so as to contact with the approximately central portions of the soundboard 95 2 and the body 4. The bridge is employed to transmit the vibration of the soundboard 2 to the body 4, whereby the latter will vibrate in unison with the soundboard, and this additional resonance improves the tone 100 100 of the musical instrument to which it is applied.

From the foregoing description taken in connection with the accompanying drawing, it will be seen that by operating the handbolts 9, the contact between the body 4 and the soundboard will be readily controlled. While one method has been disclosed for associating the body 4 with the soundboard, it is to be understood that this result can be 110 accomplished by various other methods, such as connecting the body 4 directly to the

soundboard. Moreover, while the body 4 has been described as being the same general contour as the body of a violin or the like, it will be apparent that this construction is 5 not mandatory, as the body 4 can have other forms.

Having described the invention, what is claimed as new and patentable is:—

10 The combination with a soundboard of a musical instrument and its supporting

frame, of a hollow body of substantially violin-shape having openings therein, means for adjustably supporting said body on the frame so that the same may be moved toward and away from the soundboard, and a 15 projection on said body engaging with the soundboard.

In testimony whereof I affix my signature.

JOHN W. SPRINKLE.
